(57) **CLAIM**

The ornamental design for a large hanging and spinning playground device, is shown and described herein.

DESCRIPTION

FIG. 1 is a perspective view of a large hanging and spinning playground device;

FIG. 2 is a top plan view thereof;

FIG. 3 is a front elevational view thereof; the undisclosed other sides are identical; and,

FIG. 4 is a bottom plan view thereof.

The broken line showing is included for the purpose of illustrating and forms no part of the claimed design.
